POLISHING MACHINE

John P. Cox, St. Louis, Mo., assignor to General
Motors Corporation, Detroit, Mich., a corpora-
tion of Delaware

Application July 1, 1937, Serial No. 151,426

9 Claims. (Cl. 51—59)

My invention relates to polishing machines, particularly to machines for sandpapering the metal tops of automobile bodies. The invention has for its principal object a machine which will do sandpapering automatically, including the feeding of the sandpaper across the work engaging member. The invention consists principally in a polishing shoe mounted above the work on a support that swings in a vertical plane and is capable of free tilting movement longitudinally and transversely of the work, together with automatic means for intermittently feeding sandpaper or the like across the work engaging member. The invention further consists in the polishing machine and in the parts and combinations and arrangements of parts hereinafter described and claimed.

In the accompanying drawings,

Fig. 1 is a front elevation of a polishing machine embodying my invention;

Fig. 2 is a side elevation;

Fig. 3 is a plan view looking in the directions of the arrows 3—3 in Fig. 1;

Fig. 4 is a sectional view on the line 4—4 in Fig. 3;

Fig. 5 is a sectional view on the line 5—5 in Fig. 1;

Fig. 6 is a sectional view on the line 6—6 in Fig. 1;

Fig. 7 is a detailed view of the ratchet and pawl mechanism for feeding the sandpaper;

Fig. 8 is a bottom plan view of the work engaging shoe with the cover therefor removed;

Fig. 9 is a plan view showing the mounting of the polishing machine and the drive means therefor; and

Fig. 10 is a side elevation.

The present operation of polishing or sandpapering the tops of metal automobile bodies requires the services of four workmen, each of whom sandpapers one-fourth of the top surface as the body moves longitudinally along the assembly line.

My invention greatly expedites this polishing operation by mounting the abrasive material on a shoe 1 which is automatically reciprocated transversely of the body as said body moves along the assembly line, thereby polishing the entire top surface 2 of the body 3.

Suspended from a carriage 4, secured to an overhead crane 4a that moves along tracks 5 disposed transversely of the assembly line and work 2, are a pair of hanger arms 6 whose upper end portions 7 are disposed in alignment with each other transversely of the work and extend

through holes 8 in bosses 9 projecting from said carriage 4. Collars 10 on said arms 6 engage the inner faces of the bosses 9 and nuts 11 on the threaded outer end portions 12 of said arms engage the outer faces of said bosses 9. Thus, 5 the hanger arms 6 are movable in a vertical plane about the horizontal axis formed by the end portions 7 of the arms 6. The downward movement of the hanger arms is limited by stop members 13 projecting from the carriage 4.

Said arms 6 converge toward their lower ends 14. Said ends 14 are bent into a position approaching the horizontal and to them is secured, as by welding, a hanger plate 15 having depending plates 16 in which is mounted a shaft 17 that is 15 disposed longitudinally of the work and assembly line. Pivotedly mounted on said shaft 17, preferably with a bearing sleeve 18 interposed therebetween, is a hanger block 19 through which extends a shaft 20 that is disposed at right angles 20 to said shaft 17, that is, transversely of the work. A bearing sleeve 21 is interposed between said block 19 and said shaft 20. The ends of said transverse shaft 20 extend into upstanding side walls 22 of the shoe or work engaging member 1 25 and are secured thereto by means of set screws 23 and nuts 24. The shoe proper 1 can thus pivot about said transverse shaft 20 in a vertical plane extending longitudinally of the work and said hanger block 19 can pivot about said longitudinal shaft 17 in a vertical plane transverse to the work, so that the shoe as a whole is freely tiltable, substantially universally, with respect to the work and can accommodate itself to curvature of the work, whether the work be curved longitudinally or transversely, or both, as in the case 30 of the top of the automobile body 3, diagrammatically indicated in the drawings.

The bottom or work engaging portion of the shoe has marginal ribs 25 which extend generally 40 longitudinally of the work, but have concave inner faces 26. Extending from rib 25 to rib 25 and over the outer faces 27 thereof is a pad 28 of rubber or other resilient material which is secured to the outer faces of the shoe as by screws 45 29.

Secured to the ends of the shoe 1, as by screws 30, are end plates 31 which have upwardly projecting portions 32 at one end. Mounted on a roller 33 between the tops of said projecting portions is a roll of sandpaper 34 or other abrasive material. Said sandpaper 34 passes under a steady roll 35 that is rotatably mounted between the lower portions of the end plate projections, and over a large guide roll 36 rotatably mounted 50 55

- between the end plates 31. The portion of the sandpaper 34 engaging the upper portion of said guide roll 36 is engaged by a steady roll 37 rotatably mounted between the end plates 31 and a steady roll 38 engages the lower portion of the sandpaper 34 as it leaves said guide roll 36. The ends of said lower steady roll 38 project through slots 39 in the end plates 31 and springs 40 urge said lower steady roll toward the guide roll 36.
- 10 Passing between the guide roll 36 and the lower steady roll 38 the sandpaper 34 extends across the rubber pad 28 and between a guide roll 41 and a feed roll 42 rotatably mounted between the end plates 31. Passing over the feed roll 42, the end 15 43 of the used portion of the sandpaper 34 passes between said feed roll 42 and a guide roll 44.
- The feed roll 42 is provided with a ratchet wheel 45 for cooperation with a pawl 46 that depends from one arm 47 of a feed lever (indicated generally by 48) pivotally mounted on one end 20 of the feed roll 42. A spring 49 secured to the other arm 50 of said feed lever 48 and to one end plate 31 urges the lever 48 in a direction to let the pawl 46 slide over one or more ratchet wheel teeth 51 to engage one tooth ready for the next feeding movement. An upwardly projecting contact arm 52 at the end of said feed lever 48 remote from the pawl 46 has a contact screw 53 projecting therefrom for engagement with a 25 contact bar 54 projecting from the hanger plate 15, said engagement causing swinging of the feed lever 48 to rotate the ratchet wheel 45. The operation of this feed mechanism will be further described hereinafter.
- 30 35 Secured between the lower portions of the hanger arms 6 is a brace 55 from which depends a leg 56 to the bent lower portion 57 of which is pivotally mounted a caster wheel 58 which is disposed slightly above the level of the bottom 40 of the shoe 1. Preferably said leg 57 has a telescoping sleeve portion 59 secured to the leg 56 by a set screw 60 so that the vertical position of the wheel or roller 58 may be adjusted.
- The drawings diagrammatically illustrate a 45 suitable drive mechanism for the crane 4a on which the carriage 4 is mounted, including a motor 61, drive belts 62, driven gears 63, chains 64, idler gears 65, a cross pin 66 secured to the two chains 64, and a connecting rod 67 having one 50 end pivotally mounted on said cross pin 66 and the other end on a pin 68 projecting from said crane.
- 55 As the automobile body 3 or other work moves longitudinally along the assembly line (the mechanism therefor not being shown) it will pass under the hanger arms 6, which are in the position shown in Fig. 2 until the front end of the work engages the caster wheel 58, slightly raising the hanger arms and the shoe and bringing 60 the shoe 1 into operative engagement with the top 2 of the work. Preferably the shoe and associated parts are so balanced that the shoe tilts slightly to present the working surface of the work. The shoe 1 will then move back and forth 65 across the work as the work moves longitudinally, the two movements being so correlated as to give a thorough sandpapering of all portions of the top of the work. Ordinarily, the work will be sprayed with water during the sandpapering 70 process. At one end of the travel of the shoe over the transversely curved work, the shoe will be tilted about the longitudinally extending axis so as to bring the contact screw 53 into engagement with the contact bar 54 and cause the feed 75 lever 48 to be swung to operate the ratchet wheel

45. By adjusting the position of the contact screw 53 and locking it in adjusted position by means of a lock nut 69, the stroke of the feed lever 48 can be changed so as to increase or decrease the amount of rotation of the feed wheel 45 and hence the amount of sandpaper fed at each stroke.

Obviously, the above described machine is fully automatic in its operation. The work shoe is able to conform automatically to work that is curved longitudinally or transversely or both and the resilient work pad permits the sandpaper to accommodate itself to any slight surface irregularities in the work. The sandpaper is automatically fed at intervals across the work pad so as to continuously bring fresh areas of the sandpaper into engagement with the work.

The invention is applicable to either wet or dry polishing operations and to operations using other polishing material than sandpaper.

Obviously, numerous changes may be made without departing from the invention and I do not wish to be limited to the precise construction shown.

What I claim is:

1. Automatic polishing mechanism for longitudinally and transversely curving work moving longitudinally, comprising a support pivotally mounted for vertical swinging movement above the work, a shoe suspended from said support to engage the work and freely tilttable longitudinally and transversely of the work, said shoe having marginal ribs extending longitudinally of the work, a resilient pad extending from rib to rib and secured to the outer faces thereof, a sheet of polishing material covering said resilient pad, and means for reciprocating said shoe transversely of the work as it moves longitudinally.

2. Automatic polishing mechanism for longitudinally and transversely curving work moving longitudinally, comprising a support pivotally mounted for vertical swinging movement above the work, a shoe suspended from said support to engage the work and freely tilttable longitudinally and transversely of the work, said shoe having marginal ribs extending longitudinally of the work, a resilient pad extending from rib to rib and secured to the outer faces thereof, a sheet of polishing material covering said resilient pad, means for intermittently feeding said sheet of polishing material across said resilient pad and means for reciprocating said shoe transversely of the work as it moves longitudinally.

3. Automatic polishing mechanism for longitudinally and transversely curving work moving longitudinally, comprising a support pivotally mounted for vertical swinging movement above the work, a shoe suspended from said support to engage the work and freely tilttable longitudinally and transversely of the work, said shoe having marginal ribs extending longitudinally of the work, a resilient pad extending from rib to rib and secured to the outer faces thereof, a sheet of polishing material covering said resilient pad, means actuated by the tilting of said work shoe at one end of its movement over the work for intermittently feeding said sheet of polishing material across said resilient pad and means for reciprocating said shoe transversely of the work as it moves longitudinally.

4. Automatic polishing mechanism for longitudinally and transversely curving work moving longitudinally, comprising a carriage mounted on a track extending transversely of the work some distance thereabove, means for reciprocating said

5 pivotally secured to said carriage for vertical swinging movement, said arms converging downwardly, a hanger plate secured to the approximately horizontal lower end portions of said arms and disposed longitudinally of the work, mounting plates depending from the ends of said hanger plate, a shaft mounted in said mounting plates and disposed longitudinally with respect to the work, a hanger block pivotally mounted on 10 said shaft, a shaft pivotally mounted in said hanger block transversely to said first shaft and to the work, a work shoe having upstanding ribs spaced from the sides of said hanger block and secured to said transverse shaft, said shoe having depending ribs on its lower or work face extending substantially longitudinally of the work, a resilient pad mounted over said ribs, end plates secured to the ends of said shoe and hav-

ing upstanding supports at one end, a roll of abrasive material rotatably mounted in said supports, said abrasive material being directed across said resilient pad, feed means for said abrasive material including a feed roll having a ratchet wheel secured thereto, a feed lever pivotally mounted on the end of said feed roll adjacent to said ratchet wheel, a feed pawl depending from one arm of said feed lever, a retracting spring for said feed lever, a contact arm projecting from 15 said feed lever at the end remote from said pawl, a contact screw projecting upwardly from said contact arm and a contact bar projecting from said hanger plate in position to be engaged by said contact screw when the shoe is tilted at one end 15 of its movement over the transversely curving work.

JOHN P. COX.
